U.S. Appl. No. 29/340,244, filed Jul. 15, 2009 by Silas Amos entitled "Computer Generated Icon for a Display Panel".

Primary Examiner — Susan Moon Lee*(74) Attorney, Agent, or Firm* — Arent Fox LLP(57) **CLAIM**

The ornamental design for a computer generated icon for a display panel, as shown and described.

DESCRIPTION

FIG. 1 is a front view of a computer generated icon for a display panel showing my new design.

The broken region around the graphic icon represents a portion of a display panel which is not claimed.
